UNITED STATES PATENT OFFICE.

NEWTON A. RODEN, OF JONESBORO, LOUISIANA.

ATTACHMENT FOR PLOWS.

1,107,628.

Specification of Letters Patent. Patented Aug. 18, 1914.

Application filed February 12, 1913. Serial No. 748,028.

To all whom it may concern:

Be it known that I, NEWTON A. RODEN, a citizen of the United States, residing at Jonesboro, in the parish of Jackson and State of Louisiana, have invented certain new and useful Improvements in Attachments for Plows, of which the following is a specification, reference being had to the accompanying drawings.

10 This invention comprehends certain new and useful improvements in plow attachments, and has for its primary object to provide a blade which may be readily attached to plows of various forms to convert the same into scrapers or grading machines.

Another object is to provide a blade of this character which will be of extremely simple construction and which may be readily applied after the removal of the mold 20 boards or disks.

A further object is to provide a blade of this type with means for readily attaching the same to plows of various forms and constructions without changing the construction of the implements.

With the above and other objects in view, this invention consists in certain novel details of construction, combination, formation and arrangement of parts to be herein- 30 after more fully described, claimed, and particularly pointed out in the accompanying drawings, in which—

Figure 1 is a side elevational view of my improved blade connected to plow carrying 35 beams of an ordinary gang plow in accordance with my invention. Fig. 2 is a top plan view of the same.

Referring more particularly to the drawings, in which similar reference characters 40 designate corresponding parts throughout, the numeral 1 designates my improved blade, which is of substantially rectangular form in cross section but tapers slightly toward one end. The blade is also prefer- 45 ably curved from its upper edge to its lower edge to present a concave front face and a convex rear face, the purpose of which will be readily apparent. The blade may be constructed of any suitable material and is 50 attached at its narrow end to the lower curved end of one of the plow carrying beams 2, by means of the bolts 3 secured through said lower end of the beam and through one angle of the angle iron 4. It 55 will be understood that the other angle of the angle iron 4 is secured to the blade 1 by

means of the bolts 5. The opposite end of the blade has secured thereto, as shown at 6, the downwardly directed end of the connecting beam 7, the opposite end of which is bolted to a second plow carrying beam 8, as clearly shown at 9. It will be seen that by connecting the ends of the blade 1 to the plow carrying beams 2 and 8 in this manner, the wide ends of the blade will be 60 spaced a considerable distance rearwardly of the beam 8, thus placing the blade at an angle to the line of draft of the implement.

The blade 1 is provided at its narrow end with the curved slot 1' through which one 70 of the bolts 5 is extended to permit the blade 1 to be swung upon the other bolt 5 to adjust the height of the wide end of the blade, the height being determined by the gage bar 10, which will be later fully described. After the height of the wide end 75 of the blade has been adjusted, the nuts 5' on the bolts 5 are tightened against the rear face of the blade, thus securely retaining the same in adjusted position.

The blade 1 is adjusted vertically by 80 means of the gage bar 10 which has its lower end curved downwardly and rearwardly, as shown at 11, for engagement upon the ground or other surface forwardly of the 85 wide end of the blade, while the upper end of the gage bar 10 is clamped to the side of the connecting beam 7 by means of the clamping member 12. It will be evident that by raising or lowering the gage bar 90 10, the height of the blade 1 may be readily adjusted, as occasion may require.

I have shown the narrow end of the blade as being secured to a plow carrying beam to the left side of the implement, while the wide end of the blade is connected to a plow carrying beam to the right side of the implement. It will be apparent that while this is the preferred manner of connecting the blade in the rear of gang plows, it may 100 be reversed if desired, which would require but a slight alteration of the construction and arrangement of the parts of my attachment.

From the foregoing description, it will be 105 evident that this blade may be readily attached to disk plows or any other form of plow by simply removing the disks or mold boards at the opposite sides of the implement and securing the ends of 110 the blade in position, as before described, thus making it possible to employ the im-

plement for grading and like purposes. It will be further understood that minor changes in the form of the blade and the connecting means therefor, may be made 5 within the scope of the appended claim without departing from the spirit of my invention. It will be understood however, that minor changes in the manner of connecting the blade with the sulky plow may 10 be made within the scope of the appended claim.

What is claimed is:—

The combination with the end beams of 15 an implement, of a transversely curved blade having an arcuate slot near one end and a bolt opening above said slot, an angle iron having one arm secured to one end of the blade by bolts engaged through said bolt opening and through the arcuate slot, the 20 remaining arm of the angle iron being se-

cured to one of the beams of the implement, the height of the remaining end of the blade being adapted to be adjusted by swinging the blade upon the bolt engaged through the bolt opening, thereby changing the position of the other bolt in the arcuate slot, a connecting beam having one end secured to the remaining outer beam of the implement while the opposite end of said connecting beam is curved downwardly and secured to the rear face of the blade adjacent the second end thereof, and means for gagging the height of the last mentioned end of the blade. 25

In testimony whereof I hereunto affix my 30 signature in the presence of two witnesses.

NEWTON A. RODEN.
